UNITED STATES PATENT OFFICE.

JOHN BELLEY, OF PASSAIC, NEW JERSEY, ASSIGNOR OF ONE-HALF TO PAUL MILLER,
OF NEWARK, NEW JERSEY.

LOCK.

1,209,383.

Specification of Letters Patent. Patented Dec. 19, 1916.

Application filed August 15, 1916. Serial No. 115,000.

To all whom it may concern:

Be it known that I, JOHN BELLEY, a citizen of the United States, and a resident of Passaic, in the county of Passaic and State 5 of New Jersey, have invented certain new and useful Improvements in Locks, of which the following is a specification.

The present invention relates to locks or latches for securing doors and other parts.

10 One of the objects of the invention is to provide, in a latch of simple construction, means whereby the bolt may be held in its projected position when the door is closed and in retracted position when the door is 15 open, the bolt being shot into place by the operation of closing the door.

Another object of the invention is to produce a latch, the bolt of which is combined with a dead-locking member that can be actuated from the outside by a key and from the inside by a slide.

20 A further object of the invention is to devise a latch or lock that can be manufactured on a commercial scale, or in other 25 words one which is not so difficult to produce as to be beyond the reasonable cost of such an article.

With these and other objects in view, which will more fully appear as the nature 30 of the invention is better understood, the same consists in the combination, arrangement, and construction of parts hereinafter described, pointed out in the appended claims and illustrated in the accompanying 35 drawings, it being understood that many changes may be made in the size and proportion of the several parts and details of construction within the scope of the appended claims without departing from the spirit or 40 sacrificing any of the advantages of the invention.

One of the many possible embodiments of the invention is illustrated in the accompanying drawings, in which:—

45 Figure 1 represents a view of the inside of a door and jamb provided with a latch constructed in accordance with this invention; Fig. 2 is a similar view, partly in section, the inner escutcheon plate being removed to 50 more clearly show the interior construction of the latch; Fig. 3 is a section taken on line 3—3 of Fig. 2; Fig. 4 is a section taken on line 4—4 of Fig. 2; Fig. 5 is a view similar to that illustrated in Fig. 2 with

the dead-locking member in its operative 55 position; Fig. 6 is a view similar to that shown in Fig. 4 with the elements in other positions; Fig. 7 is a vertical longitudinal section taken through the bolt casing of the latch; Fig. 8 is a section taken on line 8—8 60 of Fig. 7; Fig. 9 is a section taken on line 9—9 of Fig. 7; and Fig. 10 is a perspective view of the sliding bolt of the latch.

In the drawings, the numeral 11 indicates a latch casing, which is of tubular configuration, its front end 12 being open and its rear end 13 closed. The front end of the casing is provided with a flange 14, having holes 15 extending therethrough. The casing is inserted into a cylindrical bore 16 in the 70 door 17, said bore extending horizontally in parallel relation to the inner face of the door. The flange 14 is disposed in a suitably shaped recess 18 in the door, said recess being formed in that edge of the door which 75 abuts against the door-jamb 19. The casing is held within the bore by screws 20, passing through the holes 15 in the flange 14. In the casing 11 is slidably disposed a cylindrical latch bolt 21, fitting snugly the said casing. 80 This bolt is provided with a lug 22, projecting through a longitudinal slot 23 in the casing and through an aperture 24 in an actuating lever 25. This lever is disposed within a mortise 26 in the door, and 85 is carried by a knob-spindle 27, that is provided with a substantially square portion, extending through a similarly shaped opening 28 in the actuating lever. The knob-spindle is disposed at right angles to the 90 longitudinal axis of the latch casing 11, extends through the door and also through escutcheon plates 29 and 30. Knobs 31 are associated with the spindle for the well-known purpose. The outer escutcheon plate, 95 that is plate 29, has, preferably, made integral therewith screw-threaded nuts 32, which are located in recesses in the outer face of the door, and with these nuts mesh those of screw bolts 33, that extend through 100 the inner escutcheon plate 30, their heads 34 abutting against the inner face of the last named escutcheon plate.

In the casing 11 is arranged behind the bolt 21 a spring 35, which has a tendency to 105 project the said bolt into a keeper 36, located within a recess 37 in the door-jamb. For the purpose of keeping the bolt in its

retracted position, there is oscillatably mounted within the recess 18 upon the upper one of the two screws 20 a detent 38, in the form of a plate, that is provided with an opening 39, through which the casing 11 extends. This detent is under the tension of a spring 40, which has a tendency to force the said detent into a notch 41 in the casing, thereby bringing it in front of the bolt 21 5 when the latter is retracted and keeping the said bolt in such position. The detent has an extension 42, which is, when the door is in its closed position, located within the recess 18, but is adapted to be projected 10 through a slot 43 in the door beyond the outer face of the latter to strike against a ledge 44 upon the jamb 19, for a purpose hereinafter to be fully described.

With the actuating lever 25 is adapted to 20 coöperate a dead-locking member 45, that is slidably mounted upon the escutcheon plate 30 and is disposed within the mortise 26 in the door. This dead-locking member is attached to a pin 46, which projects through 25 a vertically arranged slot 47 in the escutcheon plate 30 and carries on its outer end a plate 48, serving as a guide for the dead-locking member. The free end of the pin is made in the form of a knob 49, to facilitate 30 the operation of the dead-locking member. In its inoperative position, the dead-locking member is held out of the path of the actuating lever 25, as clearly shown in Fig. 2 of the drawings. If it is, however, 35 shifted downward, it abuts against the said actuating lever and prevents the latter from being oscillated by the aid of the knobs 31. For the purpose of operating the dead-locking member from the outside of the door, a 40 key is used. This key is inserted through a keyhole 50 in the escutcheon plate 29, said keyhole being in alinement with a transverse recess 51 in the door. The bit of the key is adapted to engage the dead-locking 45 member 45, which is provided for this purpose with shoulders 52. In inserting the key, its pin reaches into a hole 53 in the escutcheon plate 30. With this hole is associated a keyhole guard 54, comprising a 50 plate that is pivoted at 55 to the escutcheon plate 30 and provided with a thumb-bit 56. When this guard abuts against the plate 48 (Fig. 1), the key cannot be inserted into the lock. From the inner face of the escutcheon plate 30 project into the mortise 26 studs 57, corresponding to the notches in the key-pit and serving to prevent a turning of an improper key.

The operation of this device is as follows: 60 When the door is in its closed position, the detent 38 is in the position shown in Fig. 4 of the drawings, in which its extension 42 abuts against the ledge 44 of the door-jamb, holding the spring 40 compressed. If the dead-locking member 45

is in its inoperative position (Fig. 2), the bolt 21 can be retracted from the keeper from either side of the door by turning the respective knob 31 in the proper direction. When the bolt has been retracted and the door opened, the spring 40 forces the detent into the notch 41 in the casing 11 (Fig. 6), thereby keeping the bolt retracted. In closing the door, the extension 42 strikes against the door-jamb with the result that 70 the detent is unseated from the notch 41 in the casing (Fig. 2), permitting the spring 35 to act and to project the bolt into the keeper.

The dead-locking member may be brought 80 into its operative position (Fig. 5) from the inside of the door by taking hold of the knob 49 and shifting it downward as far as the slot 47 will permit. If the parts are 85 in these positions the door can be opened from the outside by the use of a proper key only. In turning this key its bit is brought into engagement with one of the shoulders 52 of the dead-locking member, raising the latter as its rotation is being 90 completed. After this the door is opened in the manner above described. If it is intended to prevent the insertion of a key into the door, the keyhole guard 54 is brought into the position shown in Fig. 1 of the 95 drawings. The dead-locking member is adapted to be brought into its operative position from the outside of the door by turning the proper key in a direction opposite to the one in which it is rotated in unlocking 100 the door.

What I claim is:

1. In a latch, the combination with a casing, of a spring-actuated bolt therein, a knob-spindle oscillatably mounted in proximity of said casing, an actuating lever carried by said spindle and pivotally connected with said bolt for retracting the same, a spring-pressed detent extending in a plane at right angles to the longitudinal axis of said bolt for holding the latter retracted against the action of the spring co-operating with said bolt, said detent having an extension adapted to project beyond one of the faces of the door and to strike 115 against the door-jamb, whereby said detent is disengaged from said bolt upon closing the door, a dead-locking member shiftably arranged upon the door adapted to be brought into contact with said lever to prevent a motion of the latter, said member having shoulders adapted to be engaged by a key from the outside of the door, and a knob upon the inner face of the door for manually controlling said member from the 120 inside.

2. In a latch, the combination with a casing, of a spring-actuated bolt therein, a knob-spindle oscillatably mounted in proximity of said casing, an actuating lever 130

carried by said spindle and pivotally connected with said bolt for retracting the same, a dead-locking member shiftably arranged upon the door adapted to be brought into contact with said lever to prevent a motion of the latter, said member having shoulders adapted to be engaged by a key from the out-

side of the door, and a knob upon the inner face of the door for manually controlling said member from the inside. ¹⁰

Signed at New York, in the county of New York, and State of New York, this 18th day of July, A. D., 1916.

JOHN BELLEY.
